UNITED STATES PATENT OFFICE.

GUSTAVE A. KING, OF CHICAGO, ILLINOIS.

TOY.

1,340,394.

Specification of Letters Patent. Patented May 18, 1920.

Application filed May 26, 1919. Serial No. 299,681.

To all whom it may concern:

Be it known that I, GUSTAVE A. KING, a citizen of the United States, residing at Chicago, in the county of Cook and State of Illinois, have invented new and useful Improvements in Toys, of which the following is a specification.

This invention has for its object to produce a toy which can be used in several ways, and to this end it consists in a novel combination and arrangement of parts to be hereinafter described and claimed.

In order that the invention may be better understood, reference is had to the accompanying drawing forming a part of this specification, and in said drawing,

Figure 1 is a side elevation of the toy;

Fig. 2 is a central vertical section thereof, and

Fig. 3 is a face view.

Referring specifically to the drawing, the toy is a hollow cylindrical member having end walls 5 provided with inturned marginal flanges 6 which overlap or telescope to form the side or periphery of the member.

The side wall 6 is double to lend rigidity thereto. The parts are all made of tin or other light sheet metal, and the device is completely closed except for an opening 7 in its side or periphery. At the junction of the side or periphery and the ends of the device, are outstanding annular beads 8 on which the device may be rolled, the beads reducing the tendency to upset, and on the

inside of the device is a loose metal plate 35 or block 9, so that when the device is shaken it produces a rattling noise. The plate 9 is polygonal to prevent its getting stuck in the corners of the device.

At the center of each end wall 5, the same 40 is formed with a protuberance 10, which is surrounded by an annular groove 11 in said wall.

The walls 5 are flexible so that when they are alternately squeezed and released, the 45 vibration of the metal causes a warping noise, the sound issuing from the opening 7, and upon placing this opening close to the ear a roaring sound is heard. The grooves 11 increase the flexibility of the walls 5. 50

The device can also be used as a top by placing it on either end and spinning it on the protuberance 10, the same now serving as a point for the top.

The device is simple and cheap, and it 55 produces a novel and amusing toy by reason of the various ways in which it can be used.

I claim:

A toy comprising a hollow cylindrical member of resonant material having a rigid 60 side wall, and flexible end walls with annular outstanding peripheral beads at the ends of the side wall, said end walls being also provided with centrally located outturned protuberances to serve as the spinning 65 points of a top.

In testimony whereof I affix my signature.
GUSTAVE A. KING.
